US00D822232S

(12) **United States Design Patent** (10) **Patent No.:** **US D822,232 S**
(45) **Date of Patent:** **** Jul. 3, 2018**

(54) **BULB**

(71) Applicant: **Tala Energy Limited**, London (GB)

(72) Inventors: **Joseph Andrew Armitage**, London (GB); **James Rhodri Pleass**, London (GB); **Joshua James Gould Ward**, London (GB)

(73) Assignee: **Tala Energy Limited**, London (GB)

(**) Term: **15 Years**

(21) Appl. No.: **29/633,353**

(22) Filed: **Jan. 12, 2018**

Related U.S. Application Data

(63) Continuation of application No. 29/625,012, filed on Nov. 6, 2017.

(57) **CLAIM**

The ornamental design for a bulb, as shown and described.

DESCRIPTION

FIG. 1 is a perspective view of a bulb showing our new design;
FIG. 2 is a front view thereof;
FIG. 3 is a side view thereof;
FIG. 4 is a top view thereof; and,
FIG. 5 is a bottom view thereof.

The broken lines illustrate structure or features which form no part of the claimed design.
The drawings include CAD lines that represent contour and not surface decoration.

The claimed design is preferably translucent.

1 Claim, 4 Drawing Sheets
